Primary Examiner—Stella Reid

CLAIM

I claim the ornamental design for a stimulating massager, as shown and described.

DESCRIPTION

FIG. 1 is a top plan view of a stimulating massager, showing my new design;

FIG. 2 is a front elevational view thereof, the rear elevational view being identical thereto;

FIG. 3 is a right side elevational view thereof, the left side elevational view being identical thereto; and,

FIG. 4 is a bottom plan view thereof.
